US0D1060463S

(12) **United States Design Patent** (10) **Patent No.:** **US D1,060,463 S**
(45) **Date of Patent:** **** Feb. 4, 2025**

(54) **VIDEO CONFERENCE DEVICE**

(71) Applicant: **Logitech Europe S.A.**, Lausanne (CH)

(72) Inventors: **Andrew Julian Gartrell**, Walnut Creek, CA (US); **Ricardo Filipe Figueiroa Monteiro**, Walnut Creek, CA (US); **Jerry C W Huang**, Hsinchu County (TW)

(73) Assignee: **Logitech Europe S.A.**, Lausanne (CH)

(**) Term: **15 Years**

(21) Appl. No.: **29/887,184**

(22) Filed: **Mar. 17, 2023**

(51) **LOC (15) Cl.** **14-03**

(52) **U.S. Cl.**

USPC **D16/202**; D14/125

(57) **CLAIM**

The ornamental design for a video conference device as shown and described.

DESCRIPTION

FIG. 1 is a front perspective view of a video conference device showing our new design;

FIG. 2 is a rear perspective view thereof;

FIG. 3 is a bottom perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a left-side elevation view thereof; and,

FIG. 9 is a right-side elevation view thereof.

The broken lines shown in the figures show unclaimed features of a video conference device and form no part of the claimed design.

1 Claim, 6 Drawing Sheets
